(57) CLAIM

I claim the ornamental design for the grooming device, as shown and described.

DESCRIPTION

A portion of the disclosure of this patent document contains material which may be protected by copyright. The copyright owner has no objection the facsimile reproduction by anyone of the patent document or the patent disclosure, as it appears in the Patent and Trademark Office patent file or records, but reserves all other copyright rights whatsoever.

FIG. 1 is a perspective view of an embodiment of a grooming device showing my new design.

FIG. 2 is a plan view of the top of the grooming device shown in FIG. 1.

FIG. 3 is a plan view of the bottom of the grooming device shown in FIG. 1.

FIG. 4 is an exploded perspective view of the grooming device shown in FIG. 1.

FIG. 5 is a perspective view of another embodiment of a grooming device showing my new design.

FIG. 6 is a perspective view of the grooming device shown in FIG. 5 showing the top, side and back of my new design.

FIG. 7 is a perspective view of the grooming device shown in FIG. 5 showing the bottom, side and back of my new design; and,

FIG. 8 is an exploded perspective view of the grooming device shown in FIG. 5.

The broken lines shown in the drawings illustrate portions of the article and form no part of the claimed design.
